UNITED STATES PATENT OFFICE.

GEORGE SHEELY AND JOSEPH H. SHEELY, OF MARSHALLTOWN, IOWA.

SECTIONAL VEHICLE-TIRE.

1,210,219.

Specification of Letters Patent. Patented Dec. 26, 1916.

Application filed June 6, 1916. Serial No. 101,900.

To all whom it may concern:

Be it known that we, GEORGE SHEELY and JOSEPH H. SHEELY, both citizens of the United States, and residents of Marshalltown, in the county of Marshall and State of Iowa, have invented a new and Improved Sectional Vehicle-Tire, of which the following is a full, clear, and exact description.

The object of the invention is to provide a new and improved sectional vehicle tire, arranged to permit of replacing a worn out or injured section without disturbing more than the adjacent sections and without jacking up of the wheel on which the tire is used.

In order to accomplish the desired result, use is made of a shoe or a casing, preferably made in two or more sections and adapted to be fastened to the rim of the vehicle wheel, sleeves fitting into the said shoe and inflatable inner segmental tubes each having closed ends and fitting into the corresponding ends of adjacent sleeves.

A practical embodiment of the invention is represented in the accompanying drawings forming a part of this specification, in which similar characters of reference indicate corresponding parts in all the views.

Figure 1 is a face view of a vehicle wheel provided with the improved sectional tire; Fig. 2 is an enlarged cross section of the same on the line 2—2 of Fig. 1; Fig. 3 is a side elevation of one of the inner tube sections; Fig. 4 is an enlarged sectional plan view of one end of the same, the section being on the line 4—4 of Fig. 3; and Fig. 5 is a sectional side elevation of one of the sleeves.

The shoe or casing of the vehicle tire is preferably made in a number of sections 10 abutting at their ends and each section 10 is provided with the usual beads or ribs 11 adapted to be engaged with the flanges 12 of a clencher rim 13 secured to the felly 14 of the wheel. Within the shoe sections 10 are arranged sleeves 15 breaking joints with the shoe sections 10 and each having a transverse partition 16 intermediate the ends and preferably nearer one end than the other, as plainly indicated in Figs. 1 and 5. Each end of the sleeve 15 is provided with a flaring mouth 17 to permit convenient introduction of inflatable inner segmental tubes 20

each of which fits into the corresponding end portions of adjacent sleeves with the closed ends 21 of the tubes 20 in close proximity to the partitions 16. Each of the tubes 20 is provided with an air valve 22 for inflating the tube after the same is in position in the sleeves as above described. The shoe sections 10 are made in the usual manner of shoes now generally constructed, that is, are made of rubber reinforced by canvas or other similar material, and each sleeve 15 is preferably made of a textile fabric and each tube 20 is preferably made of rubber tubing with the ends pressed together and vulcanized so as to provide the closed ends 21 above referred to.

It will be noticed that a vehicle tire constructed in the manner described permits of conveniently removing a worn out shoe section 10 and replacing the same by a new one whenever it is desired to do so and without requiring jacking up of the wheel on which the tire is used. It will also be noticed that any of the sleeves 15 can be removed after the corresponding shoe sections have been removed, and the corresponding tube 20 can be removed from the adjacent removed sleeves 15 in case said tube 20 is punctured or otherwise injured and requires mending or replacing by a new one. It is understood that for removing any one of the sections, the wheel is preferably turned until such section is in uppermost position.

It is understood that by the arrangement described the sleeves 15 break joints with the shoe sections 10 and the tubes 20 break joints with the sleeves 15 into which they fit, as above explained. The partitions 16 in each sleeve 15 can be readily formed of cord or threads passed by a needle through the sleeve in a transverse direction, but we do not limit ourselves to this mode of making the partition as the same may be woven directly into the sleeve while making the latter.

Having thus described our invention, we claim as new and desire to secure by Letters Patent:

1. A sectional vehicle tire, comprising a shoe, sleeves fitting into the said shoe with their open ends abutting, each sleeve having a transverse partition intermediate its ends, and inflatable inner segmental tubes having

closed ends, each tube fitting into corresponding ends of adjacent sleeves with the closed ends at the said partitions.

2. A sectional vehicle tire, comprising a shoe, sleeves fitting into the said shoe with their open ends abutting, each sleeve having a transverse partition intermediate its ends

and nearer one end than the other, and inflatable inner segmental tubes having closed ends, each tube fitting into corresponding ends of adjacent sleeves with the closed ends at the said partitions. 10

GEORGE SHEELY.
JOSEPH H. SHEELY.
